(57) **CLAIM**

The ornamental design for a weight lifting bar as shown and described.

DESCRIPTION

FIG. 1 is a perspective view taken from the top of a weight lifting bar showing my new design;
FIG. 2 is a perspective view taken from the bottom thereof;
FIG. 3 is a top plan view thereof;
FIG. 4 is a front elevation view thereof;
FIG. 5 is a bottom plan view thereof;
FIG. 6 is a rear elevation view thereof; and,
FIG. 7 is a right-side elevation view thereof, the left side elevation view being the same.
The broken lines show portions of the weight lifting bar that form no part of the claimed design. The weight lifting bar is shown with a symbolic break in its length. The appearance of any portion of the weight lifting bar between the break lines forms no part of the claimed design.
